UNITED STATES PATENT OFFICE.

JOHN HUNTER, OF BARROW-IN-FURNESS, ENGLAND.

GAS-BURNER.

1,313,694.

Specification of Letters Patent.

Patented Aug. 19, 1919.

Application filed August 6, 1918. Serial No. 248,575.

To all whom it may concern:

Be it known that I, JOHN HUNTER, a subject of the King of Great Britain, residing at Barrow-in-Furness, in the county of Lancaster, in the Kingdom of England, have invented certain new and useful Improvements in Gas-Burners, of which the following is a specification.

This invention has reference to burners 10 for heating by gas, such as are required for domestic heating, cooking and ironing, also for soldering, the production of asbestos gas fires and other purposes.

The invention will be understood from 15 the following description reference being had to the accompanying drawings in which:—

Figure 1 is a longitudinal section of the burner, and

20 Fig. 2 is a side elevation thereof.

Referring to these figures, the burner is made in two parts. One part consists of the burner tube E at the bottom of which is the chamber B and the contracted axial 25 aperture or nozzle D, the said nozzle having a flaring entrance F with sides converging toward the nozzle, while the other side of the nozzle is flared in the opposite direction, as at G, so that its sides diverge toward the 30 sides of the burner tube E. The lower part of the burner tube above the nozzle D is provided with apertures or perforations H for the admission of air, and the chamber B at the lower part of the burner tube has 35 perforations C for the admission of air so that the gas becomes charged with air before and after it passes through the nozzle D. The other part of the burner consists of a nipple I provided with a contracted 40 nozzle A which enters the flaring mouth F, such nipple being screwed into the gas supply or service pipe or into a tubular fitting, neither of which are shown in the drawing.

The inclination of the flaring entrance 45 F is such that the angle or shoulder formed at the junction of the flaring mouth with the said nozzle D is only a little more than forty-five degrees to the axis of the burner, and the nozzle A which projects up into 50 proximity with the flaring entrance F is chamfered exteriorly at the top so that the angle of the chamfer and the angle of the flaring entrance substantially correspond but leave a space between of no considerable 55 capacity so that the gas emerging from the nozzle A draws in air through the perfora-

tions C in the chamber B on the principle of an injector, and causes the air to be drawn laterally over the jet of gas, the object being to thoroughly mingle the air with 60 the gas, increase the volume of the latter and add to the lightness of the mixture. By this means the air and gas mixture is given considerable velocity, so that it is supplied to the burner under sufficient pressure to prevent back firing and back flashing. It will be observed that the air is caused to mingle with the gas at two different points, namely in the chamber B and in the burner tube E so that a very thorough 65 mixing of the air and gas is secured.

The device utilizes the pressure of the gas from the main to produce a blow pipe flame, the gas issuing through the nozzle A under pressure thereby inducing a continuous 70 current of air to enter through the perforations C which air mixing or uniting with the gas passes through the nozzle D and is ignited at the top of the burner tube. The arrangement prevents any danger 75 of the flame burning back in the burner tube.

I declare that what I claim is:—

1. A gas burner composed of a burner tube at the bottom of which is a chamber 85 having perforations for the admission of air and a contracted axial aperture or nozzle having a flaring entrance the inclination of which is such that the angle or shoulder formed at the junction of the flaring mouth with the said nozzle is only a little more than forty-five degrees to the axis of the burner, and a gas supply nozzle which projects up into the flaring entrance and is chamfered exteriorly at the top so 90 that the angle of the chamfer substantially corresponds to the angle of the flaring entrance but leaves a space between of no considerable capacity, whereby gas emerging from the nozzle draws in air through the 95 perforations in the chamber and causes it to be drawn laterally over the jet of gas by which a more thorough mixing of the gas and air is obtained.

2. A gas burner, comprising in combination a tubular member having a cross partition adjacent the lower end thereof with a nozzle or an aperture formed centrally therein, the upper face of the cross wall or partition being concave with openings extending through the wall above and adjacent said rounded portion, the under wall 105

of the cross partition being inclined downwardly and outwardly with openings extending laterally through the wall of the tubular member adjacent the lower portion of such inclined wall; and a nipple fitting into the lower end of the tube, the upper end of the nipple being provided with a contracted nozzle which stands in alignment with the nozzle formed in the cross partition, and the upper end of said nip-

ple being inclined so that its face stands in substantial parallelism with the under face of the cross partition aforesaid.

In witness whereof, I have hereunto signed my name this 10th day of July, 1918, 15 in the presence of two subscribing witnesses.

JOHN HUNTER.
